UNITED STATES PATENT OFFICE

WALTER W. PETERSON, OF LOS ANGELES, CALIFORNIA

FOOT SUPPORTER

Application filed April 30, 1928. Serial No. 274,041.

This invention relates to and has for a main object the provision of an improved type of foot supporter adapted to be cast in a single piece from an exact pattern of a foot and formed of a light weight metal such as aluminum or an alloy thereof, or beryllium, and provided with a baked enamel finish throughout its entire area.

An important object of this invention is to provide a foot supporter based on a new and novel principle of design in which consideration is given to the shape of the entire foot which corresponds substantially to a half dome in contra-distinction to an arch or a series of arches, as viewed from the inner side of the foot, the distal ends of the metatarsals, the cuboid and os calcis defining the base of the half dome.

Contrary to the general practice of providing what have been termed as arch supporters by others seeking to correct deformities in the foot by suitably curved plates of sheet metal, leather and the like, either constructed of one or more pieces of either or both of such materials, I have provided what in effect is more than an arch supporter, and actually provides a firm support for the foot which, in addition to supporting the foot, rests beneath and extends upwardly around the back and outer side of the heel and around the inner side of the foot so as to prevent the lateral deviation of the foot from its natural longitudinal plane of alignment.

In other types of foot supports, the plates forming the supporting surfaces have been extended forwardly to points beneath the distal ends of the metatarsals, and to some extent have been curved upwardly around the posterior surface of the heel; whereas in my improved appliance I terminate the supporter rearwardly of the distal heads of the metatarsals and provide on the forward end thereof a substantially flattened portion whereby the supporter may have a firm base on the shoe. Additionally I accentuate that portion of the supporter which underlies the first metatarsal, the cuboid and the first cuneiform so that it will conform to the curvature of the inner side of the foot and will

extend upwardly around the inner side of the metatarsal and cuneiform portions.

Having thus provided a foot supporter with an accentuated portion at its rear end which extends substantially upwardly over and around the outer side of the heel and near its central portion has an accentuated upwardly extended portion over and around the instep or half dome, the slipping or slipping of the heel in the supporter and the consequent deviation of the heel in the supporter and the consequent deviation of the heel outwardly from alignment is prevented, while a firm supporting surface is provided for those portions of the foot where any weakness or deformity may exist.

In the consideration of my invention, it will be understood that no attempt is made to correct or support any so-called arches other than the half dome thus described, nor to prevent any slipping of the heel except laterally.

A particular object of my invention is to terminate the foot supporter at a point rearwardly of the ball of the foot so that it will be posterior to the maximum point of bend of the shoe, thus facilitating walking when the plates are in use and rendering the use thereof substantially more comfortable than would otherwise be possible.

Other objects may appear as the description progresses. In the accompanying drawings I have shown a preferred form of invention subject to modifications within the scope of the appended claims without departing from the spirit thereof. In said drawing,

Fig. 1 is an inside view in elevation of a foot supporter constructed in accordance with my invention and adapted for use on a right foot, the figure of a foot being shown in broken lines properly positioned with respect to the supporter.

Fig. 2 is a side elevation of the same as seen from the outer side thereof.

Fig. 3 is a front end elevation of the same as seen from line 3—3 of Fig. 2.

Fig. 4 is a rear end elevation thereof as seen from line 4—4 of Fig. 2.

Fig. 5 is a top plan view of the same.

In consideration of my invention it will be

understood that I construct my improved foot supporters by means of an improved technique which consists in making a plaster model of each individual foot, then forming a 5 pattern of the support on the model with suitable wax composition. This pattern is then used for making a metal casting which is exact in size and form to the requirements of a particular foot. The metal employed in 10 making the cast supporter is preferably of aluminum because of its light weight, and for the further reason that it is susceptible to a high polish. The metal casting is polished throughout its entire area on both its upper 15 and lower sides and is finally treated with a baked enamel, thus providing a smooth glossy surface which is low in frictional qualities and at the same time provides a comfortable, convenient, non-corrodible and non-absorptive supporter for the foot.

20 I contemplate the use of a new element known as beryllium as soon as such material is economically available, and possibly other metals or alloys which possess the qualities hereinbefore named may be employed in the construction of my supports with satisfactory results.

Referring now to the particular form of my improved supporter, it will be noted by reference to Fig. 1 that the forward terminus E of the supporter S is so disposed on the foot relative to the base of the half dome and the distal ends of the metatarsal bones that the ball of the foot may freely flex in a walking 35 operation. The front edge E is preferably formed in an irregular arc, the axis of which is substantially on the longitudinal medial line of the foot. From this medial line the end E recedes gradually in the direction of and merges with the outer edge e and the inner edge e' in convenient curves conforming substantially to the arc of the distal ends of the metatarsals. From the junction point of the front edge E and the inner edge e' the 40 supporter is bent upwardly in a gradual and graceful curve to a point beneath the upper end of the first metatarsal and the first cuneiform, as at a, thus providing a half dome-like portion which underlies the half dome of the foot and serves to support the dome against collapse and spreading in the case of 45 weakness or deformity at such points. The portion a is preferably extended up, over and around the upper end of the first metatarsal 50 and the first cuneiform so as to prevent a lateral movement of the foot inwardly from the first cuneiform. The portion a extends downwardly to a point which cuts a transverse line at the base of the os calcis.

60 As seen cross sectionally, the portion E is substantially flat while the portion a is formed on a slight arc having a chord which is disposed approximately at an angle of 45° from the base of the dome. The heel portion 65 H is cupped and the inner side thereof is

slightly bowed at h to conform to the natural curvature of the heel so that a comfortable and convenient heel socket will be provided at the rear end H. It will be observed by reference to Fig. 1 that the inner edge of the portion h is substantially above the base of the half dome, and the back h' of the heel is gradually elevated from a point on a medium transverse line of the os calcis to a point H' at the rear and on the outer side of the heel. The portion H' is continued around the outer side of the heel for a substantial distance and at an elevation above the base of the dome sufficient to prevent a lateral movement or deviation of the os calcis from its natural alignment with the other bones of the foot, as at i.

70 The portion i may terminate at any convenient point on the outer side of and opposite the astragalus, depending upon the 80 nature, form, comfort and deformity of a particular foot. From the point i the outer side of the plate is then turned downwardly at an incline i' where it merges with the outer edge e of the sole portion E.

75 It will be readily understood that it is necessary in all cases to conform the plate S to the exact requirements of certain portions of the foot and approximately to other portions of the foot, so that it is impossible to define a contour or cross sectional form of a foot supporter embodying my invention which will be applicable to all cases of foot correction. It will be noted, however, that the accentuated curved and upwardly extended portions a and H' engage respectively the inner side of the foot at the apex of the half dome and the outer side of the heel, thus preventing the lateral deviation of the bones of the foot from a natural alignment. This is 85 very important in foot correction for the reason that the tendency of a foot having a collapsing dome is to slide the os calcis laterally when the weight of the body is placed 90 on the foot.

95 When a supporter is constructed in accordance with the technique and of the form hereinbefore described, there can be no relative movement laterally between the foot and the supporter, and yet a freedom of longitudinal 105 movement and articulation is permitted.

100 I desire to emphasize the fact that in the production of my improved supporter I have considered the foot as a half dome with a collapsing apex and a deviating base instead of 110 a series of arches, and to this end have provided a distinctive foot supporter of new and novel characteristics.

115 Attention is called to the fact that a supporter of the character shown and described 125 will not absorb or induce body perspiration.

120 It will be observed by reference to the drawing that when the foot is considered as a half dome the portion a conforms substantially to the curve and plane of the half dome 130

portion of the foot and the apex of the upwardly bent and laterally inclined portion *a* is disposed adjacent the tubercle of the scaphoid, or substantially so. Also, the heel socket *H* is inclined upwardly from the point *b* near the bottom and adjacent the interior lateral surface of the astragalus around the posterior end thereof and is continued at a substantial elevation above the base of the dome around the external lateral surface of the astragalus, from which plane it declines more or less gradually as required to merge with the outer lateral edge *e*.

What I claim is:

15 1. A foot supporter comprising an integral cast metal plate having a heel socket with its outer side bent upwardly to substantially conform to the height of the os calcis and to extend around and in conformity with the heel, and its inner side bent but slightly upwardly from the base, the forward portion of said plate terminating in an arcuate line rearwardly of the ball of the foot, and an inner portion in the form of a half dome 20 bent upwardly beneath and around the joint between the metatarsal and cuneiform portions and having its periphery disposed above the level of the arch.

25 2. A foot supporter formed of an integral piece of cast metal and provided with a heel socket bent upwardly around the outer side of the heel and having its edge substantially flush with the top of the os calcis, an instep portion bent upwardly and inclined laterally from the base to a point beneath and 30 having its apex adjacent the tubercle of the scaphoid, the forward end of said support being arcuately formed and terminating posteriorly of the distal heads of the metatarsals.

35 3. A foot supporter formed of a single piece of cast metal and having its anterior end arranged to be disposed posteriorly of the distal heads of the metatarsals, an inner lateral portion bent upwardly and inclined laterally, and its posterior end portion forming 40 a heel socket and bent upwardly around the outer lateral surface and outer portion of the heel so that its periphery will be substantially flush with the upper side of the os calcis.

WALTER W. PETERSON.
